COMBINED STOKER AND FIRE DOOR

Paul A. Ketchpel, West Englewood, N. J., assignor, by mesne assignments, to The Standard Stoker Company, Inc., New York, N. Y., a corporation of Delaware

Original application October 6, 1931, Serial No. 567,215. Divided and this application October 18, 1933, Serial No. 694,021. In Canada September 21, 1933

9 Claims. (Cl. 110—101)

This invention relates to firedoors which are employed to close the firing opening of a furnace and more particularly to that type of firedoor which forms a roof or other wall portion of a stoker feed conduit adapted to deliver the fuel into the furnace through the firing opening.

This application is a division of my copending application Serial No. 567,215 filed October 6, 1931 and entitled as above.

10 The main object of the present invention is to provide in a stoker of the scatter feed type that delivers fuel into the furnace through the firing opening, which opening is covered by a pressure fluid operated door serving also as a roof or other 15 wall portion for the stoker discharge conduit delivery mouth, a novel control mechanism which is arranged to control the operation of the stoker in timed relation with the pressure fluid means for operating the firedoor. By this arrangement, 20 whenever the firedoor is to be opened by pressure fluid means for manual firing or for inspection of the furnace, the operation of the stoker fuel conveying means is interrupted so that the fuel at the stoker discharge conduit delivery mouth 25 may not fall onto the cab deck when the door is opened. This phase of the invention also contemplates the provision of added means in the control mechanism whereby the fuel at the stoker discharge conduit delivery mouth above the 30 level of the distributing means is projected into the furnace prior to the opening of the firedoor, thereby allowing the full use of the firing opening for inspection or manual firing of the boiler.

On the drawings

35 Fig. 1 is a central vertical longitudinal view of the rearward portion of a locomotive showing the invention in position with portions broken away;

Fig. 2 is an elevation of the boiler backwall 40 showing the invention partly in section;

Fig. 3 is a view similar to a portion of Figure 2 showing the control mechanism in one of its phases;

Fig. 4 is an enlarged vertical longitudinal section view through the backwall and the firing opening showing the construction of the novel flexible firedoor;

Fig. 5 is a sectional view of a control valve; and

50 Fig. 6 is a sectional view showing the latch arrangement for holding the door in its uppermost position.

The invention is shown as being applied to a locomotive A having a firebox 10, the grates 11 55 and a firing opening 12 in the firebox backwall

13. Extending rearwardly of the backwall 13 is a cab 14, provided with a deck 15 which is below the lower marginal edge of the firing opening 12. A stoker generally designated at B extends forwardly from the tender (not shown) and includes a conduit 16 leading from the tender fuel bin having a screw conveyor 16a therein for advancing fuel therethrough and a riser conduit 80 including a curved nozzle or discharge conduit 17 secured to the backwall 13 and a head portion 81 surmounting the discharge conduit 17 and arranged to discharge fuel into the firebox through the firing opening 12. The conduit 16 and the discharge 17 are flexibly related at their adjacent ends as at 18 to permit articulation therebetween. A distributor plate 19 extends forwardly from the discharge conduit 17 through the firing opening 12 and, in conjunction with a pressure fluid head 20, distributes fuel to all parts of the fire. The pressure fluid head 20 is located rearward of the distributor plate 19 and is arranged to issue blasts of pressure fluid through the jet openings 21 in its front face 22. Lead lines 23 supply pressure fluid such as steam to the distributor head 20. The discharge conduit 17 is truncated at its upper portion as at 24 in substantially the plane of the distributor plate 19 to form a delivery mouth 25 which flares laterally to substantially the width of the firing opening 12.

30 A firedoor C for the firing opening 12 is arranged to move up and down and in its lowered position assumes a rearwardly and downwardly curving configuration indicated at 26 and rests upon the truncated portion of the discharge conduit forming a closure therewith for the opening 12 against outside exposure. In this position the firedoor C extends a sufficient distance above the plane of the distributor plate 19 to allow the column of fuel advancing through the discharge 35 conduit to assume its angle of repose with the front face 22 of the distributor head 20.

40 The movable door C comprises a flat plate-like portion 27 and a flexible portion 28 depending therefrom. The flexible portion 28 includes the segments 29 which have their adjacent faces curved and are secured to a flexible member 30 as by means of the rivets 31. The opposite ends 45 32, 32a of the plate-like portion 27 and 33, 33a of the segments 29 are received in the races 34, 34a in the sidewalls 35, 35a, respectively, which are formed integral with the door frame F secured to the backwall 13 for receiving the sliding door C. The sidewalls 35, 35a extend rearward from the lower portion of the door frame F 50 55

and are spaced apart a distance equal substantially to the width of the stoker discharge conduit mouth portion. These side walls form continuations of the side walls of the riser conduit 5 80 constituting supporting walls for the fuel discharged from the riser conduit. A transversely extending plate-like member or brace 82 adjacent the upper marginal edge of the firing opening connects the upwardly extended portions of 10 the side walls 35 and 35a. The contiguous edges of the upper end of the rear wall of the conduit 80, the transverse brace 82 and that portion of the side walls 35, 35a therebetween form an aperture in the upper side of the discharge conduit. It will be noted that the horizontal distance between the longitudinal extremities of the aforesaid aperture is greater than the longitudinal horizontal distance across the feed conduit adjacent the lower extremity of said aperture, which lower extremity is, of course, the upper edge of the rear wall of the conduit and the other extremity is formed by the transverse brace 82. The door C forms a movable closure for the aperture and as such also may be considered as a firedoor for the firing opening 12.

The door C may be power operated and for this purpose a motor cylinder 36, housing a piston 37 is attached to the door frame F. The piston 37 is operatively connected to a lever 38 which is fulcrumed as at 39 and connected to the first plate-like portion 27 of the door C as by means of the roller 40 which is received by the channelled portion 41 of the arm 38. A handle 42 extending outwardly from said arm 38 is provided for the manual operation of the door C which may be retained in an opened position by means of the latch 43 engaging the lug 43a formed on said door. Pressure fluid, such as compressed air, is supplied to the motor cylinder 36 by the lead 44 for power operation of the door.

A control mechanism, generally indicated at 45 controls the supply of compressed air for the opening of the door C and is also arranged to 45 interrupt the operation of the stoker in a manner as will now be described.

The control mechanism 45 comprises a body 46 encasing the chambers 47 and 48 which house the valves 47a and 48a respectively. A lead 49 50 supplies compressed air to the chamber 47 for admission to the lead line 50 when the valve 47a is raised as by means of the lever arm 51 movable by pressure on the pedal arm 52. Steam is supplied by the pipe 53 to the chamber 48 from 55 whence it passes into the pipe 54 for supplying steam for the stoker prime mover, diagrammatically shown at M. The valve 48a is provided with a stem 55 to which is secured a spring 56. The spring 56 rests on an extension 60 51a of the lever arm 51 and is of a suitable strength, to cause the valve 48a to be seated, against the pressure in the steam pipe 53 when the lever arm 51 is raised.

Suppose now, that the stoker is in operation 65 delivering fuel to the firebox and the door C is closed, and the fireman wishes to open the door. He depresses the pedal arm 52, causing the free end of the lever arm 51 to be raised. The lever arm 51 in its upward movement contacts the 70 spring 56, pushes it, together with the attached valve stem 55 and valve 48a upwardly to seat the valve 48a, thereby interrupting the passage of steam from the steam supply pipe 53 to the pipe 54 and as a result halting the operation of the 75 stoker. Further, pressure of the pedal arm 52

will cause the lever arm 51 to compress the spring 56 so that the lever arm 51 may travel upwardly a sufficient distance to unseat the valve 47a, allowing compressed air to pass from the lead 49 into the lead 50 to supply compressed air to the motor cylinder 36 through a regulating valve 57 which serves to connect pressure fluid lines 58 and 59, each of which branches from the steam pipe 53 and to connect the compressed air lines 50 and 44.

The regulating valve 57 comprises a cylinder 70 housing a valve member 71 therein which is provided with the piston 60 and the stem 61 recessed as at 62 so that when the piston 60 is moved upwardly, the pressure fluid lines 58 and 15 59 are in communication with each other. A fluid line 63 branches from the pressure fluid line 58 and communicates with a chamber or header 64 at the rear of the discharge conduit 17, the header 64 being arranged to issue blasts of pressure fluid forwardly therefrom at about the plane of the distributor plate 19 for projecting into the firebox the column of fuel which is above the truncated portion 24 of the discharge conduit, prior to the opening of the firedoor C. 20 25

Branching from the steam pipe 53 is a lead 65 which supplies steam to the pressure fluid head 20 through the lead lines 23 which branch from said lead 65. The fluid leads 63 and 65 are connected by a check valve 66 which normally is seated as shown in Figure 2 by the pressure in the lead 65. The fluid leads 58, 59 and 65 are provided with the valves 58a, 59a and 65a respectively, the valve 58a being normally closed, and being opened only when it is desired to project forwardly the fuel in that portion of the discharge conduit mouth portion rearward of the steam head independently of the use of the regulating valve. The valve 59a is preferably opened to admit steam more freely through the lead 59 and hence into the recess 62 of the valve stem 61 than is allowed to pass through the valve 65a of the pressure head lead 65. 30 35

The cylinder 70 of the regulating valve 57 is covered by a cap 72 having an atmospheric opening 73 in the flange 74 communicating with said cylinder and is provided with a recess 75 suitable to accommodate the extension 77 of the piston 60. A controllable valve 78 is threaded into the cap 50 72 to control the size of the atmospheric opening 79 which is in communication with said recess 75. 45

By referring to Figures 2, 3 and 5, it will be observed that when the pedal arm 52 is depressed to interrupt the operation of the stoker 55 driving engine, a further pressure thereon will cause the lever arm 51 to raise the valve 47a providing communication between the compressed air line 49 and the lead 50 and permitting compressed air to enter the lead 50 from the lead 49 60 thereby raising the piston 60 and the stem 61 thereof. The upward movement of the piston 60 will then connect the pressure fluid leads 58 and 59 causing the relatively high pressure of steam 65 to enter the branch lead 63 for supplying steam to the chamber 64 for projecting into the firebox the column of fuel above the distributor plate 19 at the rear thereof. At the same time, the higher steam pressure in the lead 63 will unseat the check valve 66 as shown in Figure 3, thereby admitting 70 higher steam pressure to the pressure fluid head 20 for assisting the projection of fuel into the firebox.

A short interval after the valve member 71 in its upward movement has effected communication 75

between the leads 58 and 59 through its recessed portion 62, it effects in its continued upward movement, communication between the compressed air lines 50 and 44 when the piston 60 is raised above the point at which the line 44 opens into the cylinder 70. Communication between the lines 50 and 44 being established, compressed air passes from the line 50 into the line 44 and thence to the motor cylinder 36 for opening the door C.

It will be understood that the upward movement of the piston 60 from the position shown in Figure 2 to that shown in Figure 3 will be almost instantaneous being admitted by the atmospheric opening 73 thus allowing the pressure fluid leads 58 and 59 to be connected quickly, permitting steam to pass from the supply pipe 53, through the lead 59, into the cylinder 70, then successively through the leads 58 and 63 to the header 64, from which steam is emitted for projecting the fuel forwardly which is rearward and above the plane of the distributor plate. The further upward traverse of the piston 60 will be at a slower rate of speed commensurate with the size of the atmospheric opening 79 as controlled by the valve 78 for allowing the air in the recess 75 to be compressed and evacuated by the upward movement of the extension 77 of the piston 60. Thus, after the pressure fluid leads 58 and 59 are quickly connected, they will remain in communication with each other for an interval of time, as regulated by the valve 78, sufficient to project all of the fuel forwardly which is rearward of the distributor plate and above the plane thereof.

From the foregoing it will be apparent that I have provided a novel stoker control mechanism in conjunction with a pressure fluid operated door which is particularly useful and advantageous for use with stokers which discharge fuel through the firing opening closed by a firedoor forming a roof or other wall portion for said stoker discharge mouth.

I claim:

1. In combination with a furnace having a firing opening, a stoker for delivering fuel from a source of supply to said firing opening including a riser conduit having a lower inclined portion and an upwardly and forwardly curved upper portion embracing said firing opening, an upwardly and downwardly movable door in said curved upper portion providing access to said firing opening, pressure fluid operated means for operating said stoker, pressure fluid operated means for opening said door, a supply line for delivering fluid under pressure to said stoker operating means, a supply line for delivering fluid under pressure to said door opening means and mechanism arranged to interrupt the delivery of pressure fluid to said stoker operating means and to deliver pressure fluid to said door opening means thereafter.

2. In combination with a firebox having a backwall provided with a firing opening therethrough, a stoker having a discharge conduit associated therewith, said discharge conduit attached to said backwall and arranged to deliver fuel from a source of supply to said firing opening, a lead for supplying fluid under pressure for operating said stoker, a hood portion surmounting said discharge conduit and embracing said firing opening, an opening in said hood portion permitting access to said firing opening, a door for the opening in said hood portion, a motor for opening said door, a line for supplying pressure fluid to said motor,

and mechanism for controlling the flow of fluid through said lead and through said line, said mechanism being arranged to interrupt the flow of pressure fluid through said lead and to admit pressure fluid to said line thereafter.

3. In combination with a firebox having a backwall provided with a firing opening therethrough, a stoker having a discharge conduit associated therewith, said discharge conduit being arranged to deliver fuel from a source of supply to said firing opening, a prime mover for operating said stoker, a lead for supplying pressure fluid to the prime mover, a hood portion surmounting said discharge conduit and embracing said firing opening, an opening in said hood portion permitting access to said firing opening, a door for the opening in said hood portion, a motor for opening said door, a lead for supplying pressure fluid to said motor, and mechanism for controlling the flow of pressure fluid through said leads, said mechanism being arranged to interrupt the flow of pressure fluid to said stoker prime mover and to admit pressure fluid to the door opening motor thereafter.

4. In combination with a firebox having a backwall provided with a firing opening therethrough, a stoker having a discharge conduit associated therewith, said discharge conduit attached to said backwall and having a mouth portion adjacent said firing opening for the delivery of fuel to said opening, a fuel distributor plate arranged to receive fuel from said discharge conduit, a pressure fluid head immediately rearward of said distributor plate for projecting the fluid into the firebox, a lead for supplying pressure fluid to said head, a door rearward of said firing opening having a rearwardly and downwardly inclined portion serving as a roof for said discharge conduit mouth portion, a motor for opening said door, a lead for supplying pressure fluid to said motor, a prime mover for said stoker, a lead for supplying pressure fluid to said prime mover, mechanism for controlling the flow of pressure fluid through said prime mover and motor supply leads, said mechanism being arranged to interrupt the flow of pressure fluid through said prime mover supply lead and admit pressure fluid to said motor supply lead thereafter, a pressure fluid chamber rearward of said pressure fluid head arranged to issue blasts of pressure fluid across said discharge conduit mouth portion, a lead for supplying pressure fluid to said chamber, and valve mechanism interposed in said motor supply lead and said chamber supply lead arranged to admit pressure fluid to said chamber and to said door opening motor.

5. In combination with a firebox having a backwall provided with a firing opening therethrough, a stoker having a discharge conduit associated therewith, said discharge conduit attached to said backwall and having a mouth portion adjacent said firing opening for the delivery of fuel to said opening, a fuel distributor plate arranged to receive fuel from said discharge conduit, a pressure fluid head immediately rearward of said distributor plate for projecting the fuel into the firebox, a lead for supplying pressure fluid to said head, a door rearward of said firing opening having a rearwardly and downwardly inclined portion serving as a roof for said discharge conduit mouth portion, a motor for opening said door, a lead for supplying pressure fluid to said motor, a prime mover for said stoker, a lead for supplying pressure fluid to said prime

- 5 mover, mechanism for controlling the flow of pressure fluid through said prime mover and motor supply leads, said mechanism being arranged to interrupt the flow of pressure fluid through
5 said prime mover supply lead and admit pressure fluid to said motor supply lead thereafter, a pressure fluid chamber rearward of said pressure fluid head arranged to issue blasts of pressure fluid across said discharge conduit mouth
10 portion, a lead for supplying pressure fluid to said chamber, and valve mechanism interposed in said motor supply lead and said chamber supply lead for admitting pressure fluid to said chamber and to said door opening motor, said valve mechanism
15 arranged to admit pressure fluid to said chamber before pressure fluid is admitted to said door opening motor.
6. In combination with a furnace having a firing opening, a stoker having a discharge conduit arranged to deliver fuel to said firing opening, a hood portion surmounting said discharge conduit and embracing said firing opening, a door in said hood portion providing access to said firing opening, a distributor plate extending forwardly
20 from the upper forward edge of said discharge conduit through said firing opening, a pressure fluid distributor head adjacent the rear of said distributor plate, a pressure fluid chamber at the upper rearward edge of said discharge conduit
25 arranged to issue blasts of pressure fluid across said discharge conduit mouth portion, means for opening said door, means for operating said stoker and mechanism arranged to interrupt the operation of the stoker, said mechanism arranged
30 to increase the fluid pressure in said distributor head and admit pressure fluid to said pressure fluid chamber at an interval after said interruption, and thereafter to open said door.
7. In a firebox having a wall provided with a
40 firing opening therein, a casing communicating

with said firing opening, means for delivering fuel to the firing opening through said casing, said casing having an aperture therein opposite the firing opening, a door arranged to form a closure for said aperture, means for opening said door and mechanism for rendering the fuel delivery means inoperative, said mechanism being arranged to render said door opening means operative thereafter.

8. In a firebox having a wall provided with a firing opening therein, a stoker conduit in communication with the firing opening, means for delivering fuel through the stoker conduit, a door forming a part of the stoker conduit, power actuated mechanism for opening the door and power actuated mechanism for operating said fuel delivery means, a line for supplying fluid under pressure to said door opening mechanism, a lead for supplying fluid under pressure to the mechanism operating said fuel delivery means, a valve in said line and a valve in said lead, and mechanism for successively closing said last named valve and opening said first named valve.

9. In a firebox having a wall provided with a firing opening therein, a stoker having a casing communicating with said firing opening, said casing having an aperture therein opposite the firing opening, a door arranged to form a closure for said aperture, a pressure fluid chamber at the rear of said casing arranged to emit blasts of pressure fluid against the fuel in said casing and projecting it through said firing opening, means for opening said door, means for operating said stoker and mechanism arranged for successively interrupting the operation of said stoker, thereafter admitting pressure fluid to said pressure fluid chamber and thereafter rendering said door opening means operative.

PAUL A. KETCHPEL 40
